UNITED STATES PATENT OFFICE.

JOHN JOSEPH TEARNEY, OF TORONTO, AND GEORGE LAING ALEXANDER, OF AURORA,
ONTARIO, CANADA.

HUMIDOR.

1,220,376.

Specification of Letters Patent. Patented Mar. 27, 1917.

Application filed November 29, 1915. Serial No. 63,991.

To all whom it may concern:

Be it known that we, JOHN JOSEPH TEARNEY and GEORGE LAING ALEXANDER, residents of 136 Balmoral avenue, in the city of 5 Toronto, and the town of Aurora, respectively, in the county of York, Province of Ontario, in the Dominion of Canada, have invented certain new and useful Improvements in Humidors, of which the following 10 is a specification.

The invention relates to improvements in humidors, as described in the present specification and illustrated in the accompanying drawings that form part of the same.

15 The invention consists essentially in the novel means employed whereby tobacco of the cigarettes or cigars is maintained in a moist condition by means of a dampening arrangement in a particular form of such 20 devices.

25 The objects of the invention are to keep cigars and cigarettes in handy devices for instant use in a fit condition for smoking and generally to provide a simple, serviceable and cheap article for the smoker.

In the drawings, Figure 1 is a sectional perspective view of the device.

Fig. 2 is a detail vertical sectional view showing the arrangements of the side walls.

30 Referring to the drawings, 1 is the outer casing which is here shown in open box like form having standing upwardly from the bottom thereof a central partition 2, the latter having at the top thereof the curved recess 3 and terminating at each end adjacent to the walls of the said casing 1.

35 4 is the inner casing having the slot 5 at the top thereof corresponding to the recessed top end of the partition 2, said partition just 40 extending into the slot 5.

The end walls of said inner casing 4 toward the bottom thereof are slotted at 5a.

45 6 is a zinc lining extending over the inner surface of the walls of the casing 1.

7 is a zinc covering on each side of the partition 2, said linings 6 and 7 being to protect the wood from moisture.

50 8 is a zinc lining covering the underside of the top of the inner casing and extending downwardly therefrom and having slots therein corresponding to the slots 5a in said casing.

9 are partitions preferably formed of zinc and sloping downwardly from the upper edges of the slots 5 to the central partition 2 and then turned backwardly and secured on the under sides of the slots 5a and, forming the moisture chambers 10 for the reception of dampening substances, such as wet blotting papers or other suitable pads, the 60 moisture from which flows through the perforations in said partitions.

11 are pins extending outwardly from the ends of the inner casing 4 and sliding in the grooves 12 in the outer casing 1 to prevent 65 said inner and outer casings from becoming disengaged from each other.

It will now be seen that the cigarettes are contained within the inner casing and supported on the inclined ways formed by the 70 partitions 9 over the moisture chambers 10, therefore the tobacco of the said cigarettes is retained in a comparatively moist state.

The operation of the device is of course very simple as when the inner casing is 75 raised the inner edges of the partitions 9 stop adjacent to the top side edges of the partition 2 so that when the said inner casing is lowered one cigar or cigarette will remain in the recess 3, but as there are already 80 devices operated somewhat similarly the novelty of this invention consists in the specific construction and in the novel means for combining a humidor and a delivering apparatus.

85 What we claim is:

A cigarette box or the like comprising a stationary section having a central partition grooved at the upper end and extending across the box and a movable section telescopically arranged within said stationary section and having fixed shelves inclined downwardly to said partition and adapted to elevate the cigarettes to said groove, said shelves being perforated and containing absorbent pads adapted to deliver water vapor through said perforations.

Signed at the city of Toronto, Province of Ontario, this 14th day of October, 1915.

JOHN JOSEPH TEARNEY.
GEORGE LAING ALEXANDER.
